UNITED STATES PATENT OFFICE.

JOHN McCARTEN AND ALFRED GEORGE MATTSSON, OF DETROIT, MICHIGAN.

FURNACE.

Application filed March 31, 1922. Serial No. 548,301.

Our invention relates to a new and useful improvement in a furnace and has for its object the provision of a furnace which will be simple in structure, economical of manufacture and highly efficient in use.

Another object of the invention is the provision in a furnace of a bridge wall having a fluid compartment therein.

Another object of the invention is the provision in a furnace of a baffle having a fluid compartment therein.

Another object of the invention is the provision of a furnace having a maximum amount of heating surface with a simplicity of structure.

Another object of the invention is the provision of a furnace having a fluid container formed from a single casting and having means for supporting and enclosing said container.

Another object of the invention is the provision of a bridge wall having air ducts communicating with the combustion chamber of the furnace and with the atmosphere.

Other objects will appear hereinafter.

The invention consists in the combinations and arrangement of parts hereinafter described and claimed.

The invention will be best understood from a reference to the accompanying drawings which form a part of this specification and in which,

Fig. 1 is a front elevational view of the invention with parts removed,

Fig. 2 is a longitudinal vertical sectional view of the invention,

Fig. 3 is a front elevational view of a modified form of the invention showing parts removed,

Fig. 4 is a longitudinal vertical sectional view of a modified form of the invention,

Fig. 5 is an elevational view of the baffle used in the invention,

Fig. 6 is a sectional view of the bridge wall used in the invention.

The invention is designed for use principally with bituminous coal and similar carbonaceous fuel although it will operate equally well with wood or anthracite coal.

The preferred form of construction comprises a fluid container 9 which is provided with a fluid compartment 10. The member 9 is cast in a single piece and is arcuate in form, thus affording a very simply constructed container. The member 9 rests

tending L shaped supporting members 11 and 12 which extend along both sides of the furnace, said members 11 and 12 being respectively provided at intervals with reinforcing brackets 13 and 14 which are cast integral with the supporting members. Resting upon the brackets and enclosing the container 9 is a shell 15, which is spaced from the container 9 so as to provide a flue for the travel of the gases from the rear of the furnace to the smoke-stack 41. A plate 16 is provided which serves as the front wall of the furnace from the top thereof to the level of the upper surface of the supporting members, an additional plate 16' serving as the lower portion of the front wall and being secured by bolts or other suitable means to the supporting members. A plate 17 serves as the rear wall of the furnace and is secured to the forward wall by means of stay rods 18. Projecting inwardly from the supporting member 12 is a flange 21 upon which is rested one end of the grate 22, the opposite end thereof being supported by a flange 23, 80 on the inner surface of the supporting member 12. The member 24 which acts as a reinforcing member for the supporting members 11 and 12 extends transversely thereof. A flange 19 is provided on the member 16' which abuts against a flange 20 formed on the lower end of the wall 16, said flanges being securely fastened together. Extending rearwardly from the member 24 and resting on one end thereof is a plate 25 90 which is provided at its opposite end with a flange 25' which is securely bolted or riveted to the rear wall of the furnace, at the lower portion thereof which comprises a plate 26. Mounted within the combustion chamber is a bridge wall 27 which is provided with a fluid compartment 28, an inlet pipe 29 being provided for delivering water to the interior of said bridge wall. Projected vertically through the bridge wall 27 and 100 communicating with the space above the bridge wall and the space below the same are tubes 30 which serve to conduct air to the combustion chamber. A baffle 31 is connected by a hollow nipple 32 to the container 9 so as to bring the baffle and the container into communication with each other, the baffle being a single casting and having a compartment therein for the delivery of fluid thereto, a pipe 31' being connected therewith which communicates with feed pipe 35 or a suitable source of fluid. The

baffle is cast arcuate and is threaded onto the nipple 32. By constructing the baffle in this manner it is easily assembled in position and is readily removable when it is desired to remove it. It is apparent that the baffle, besides functioning in the ordinary manner as a baffle also acts as a heating surface and thereby serves to increase the efficiency of the furnace. It is apparent that this is also true of the bridge-wall. Delivery pipes 35 and 36 which are connected to some suitable source of fluid supply communicate with the container at the opposite sides thereof. These delivery pipes may communicate with the container at either the front or the rear thereof, depending upon the convenience of attachment in each particular case, and for this purpose openings are made in the end walls of the container at each side of each end wall, the openings which are not being used being closed by suitable plugs. Outlet pipes 38 and 37 are provided for delivering the hot water to the radiators, the number of said pipes being optional in each case. The form shown in Figs. 1 and 2 are of a water heater and the forms shown in Figs. 4 and 5 relate to the use of the device for a steam heater which will be described hereinafter. In the form shown in Fig. 3 and Fig. 4, a delivery pipe 40 is in communication with the bridge wall and projects exteriorly of the furnace and may be attached or connected to the main delivery pipe at any convenient location. Provided in the end walls of the furnace are openings 42 and 43 which communicate respectively with the passages 45 and 45' provided between the container and the shell so that the dust and dirt which is brushed from the upper surface of the container may thereby be removed, although it has been found in actual experience that most or all of the dirt and soot which is deposited in said passages is very readily burned by the hot gases passing therethrough. Openings 44 are provided in the end walls adjacent the upper portion thereof to allow the operator to brush the dirt and soot from the upper surface of the container into the passages 45 and 45'. A fire box door 46 and an ash pit door 47 are provided which are of the usual type. In the rear wall is provided a door 48 which allows access to the rear end of the combustion chamber. A suitable coating of asbestos 49 is utilized on the boiler in the ordinary manner and for the ordinary purpose.

With a device constructed as described there is provided a furnace which is simple of structure and at the same time very durable. By forming the various parts as described the number of parts to a furnace is greatly reduced and the cleaning of the furnace is brought to a greater degree of simplicity, as well as reducing the costs of assembling a furnace of this type. A furnace

is also provided which allows the use of any kind of fuel with considerable saving resulting from the increased heating surface and from the fact that the heating surface remains cleaner than in furnaces such as are now customarily used. The increased combustion resulting from the introduction of air into the furnace and the manner of introducing the same also add to the efficiency of the device.

In Fig. 3 and Fig. 4 there is shown a modified form of the invention whereby the furnace is utilized for steam heating instead of for hot water heating. A steam dome 50 is mounted on the shell and is connected to the container by means of pipes 51 and 52 and to the bridge wall by means of the pipe 53. A delivery pipe 54 serves to conduct the steam from the dome 50. In both cases, whether the device is used for a hot water heater or a steam heater stay bolts or ribs are cast integral with the interior of the container, serving to reinforce the walls of the container so as to prevent any warping or the same or any bulging thereof.

While we have illustrated and described the preferred forms of construction we do not wish to limit ourselves to the precise forms of structure shown but desire to avail ourselves of such variations and modifications as come within the scope of the appended claims.

Having thus described our invention what we claim as new and desire to secure by Letters Patent is:

1. A boiler comprising a semi-cylindrical fluid container having semi-cylindrical walls in spaced relation; end walls mounted thereon and integral therewith; spaced longitudinally extending L-shaped supporting standards adapted for engaging the edges of said container for supporting the same, the inner diameter of said container being equal to the space separating said standards; supporting brackets projecting inwardly from the inner surface of each of said supporting standards and above the bases of said standards; grates mounted on said brackets and positioned below the point of engagement of said container with said supports; outwardly projecting brackets on said supporting standards for reinforcing the same; a semi-cylindrical outer shell supported along its edges by said supporting standards and in spaced relation to said container; and a front and rear wall co-operating with said outer shell for enclosing said container.

2. A boiler comprising a semi-cylindrical fluid container having semi-cylindrical walls in spaced relation; end walls mounted thereon and integral therewith, said container comprising a single casting; spaced longitudinally extending L-shaped supporting standards, each having its legs vertically extending and engaging with its base the

edges of said container for supporting the same, the inside diameter of said container being equal to the space separating said standards; a transversely extending bracing member positioned between said standards for reinforcing the same; a supporting bracket projecting inwardly from the inner surface of each of said supporting standards, said brackets being positioned below the upper edge of said supporting standards and above the bases of said standards; grates mounted on said brackets and positioned below the point of engagement of said container with said supports; a plurality of

reinforcing brackets mounted on the outer surface of said supporting standards for reinforcing the same; a semi-cylindrical outer shell supported along its edges by said supporting standards and in spaced relation to said container, the end, front and rear walls co-operating with said outer shell for enclosing said container.

In testimony whereof we have hereunto set our hands at Detroit, in the county of Wayne and State of Michigan.

JOHN McCARTEN.

ALFRED GEORGE MATTSSON.
